UNITED STATES PATENT OFFICE.

FRED LACEY, OF LOWELL, MASSACHUSETTS, ASSIGNOR TO DRAPER CORPORATION, OF HOPEDALE, MASSACHUSETTS, A CORPORATION OF MAINE.

FILLING-THREAD CONTROLLER.

1,350,613.

Specification of Letters Patent. Patented Aug. 24, 1920.

Application filed August 25, 1919. Serial No. 319,608.

To all whom it may concern:

Be it known that I, FRED LACEY, a citizen of the United States, residing at Lowell, in the county of Middlesex and State of Massachusetts, have invented an Improvement in Filling-Thread Controllers, of which the following description, in connection with the accompanying drawings, is a specification, like characters on the drawings representing like parts.

The invention to be hereinafter described relates to filling replenishing looms, and more particularly to the means for controlling or positioning the filling thread leading from the filling carrier to be discharged or ejected from the shuttle when filling is to be replenished.

It has been proposed heretofore to part or cut the filling between the cloth selvage and the filling carrier to be abandoned, and then carry the end leading from the cloth selvage frontwardly to position it for the action of the temple thread cutter. In practice it has been found convenient to mount the parter or thread cutter on the shuttle feeler, or to otherwise so arrange it that the parting and clamping means may be normally maintained in a front position and be moved to a rear or operative position only on call for filling replenishment. When the shuttle feeler and its accompanying parter and clamp move frontwardly after having parted the filling, it carries the end of the filling leading from the cloth selvage frontwardly, but the distance between the cloth selvage and parter and clamp when the latter is in its rearward or operative position is less than when it is in its front position, consequently, some provision must be made for producing a sufficient length of thread between the cloth selvage and parter and clamp to prevent breaking of the thread between the cloth selvage and parter and clamp as the latter move frontwardly.

When the shuttle feeler and parter and clamp move to rearward position, the filling thread leading from the cloth selvage to the filling carrier in the shuttle is to be abandoned, should be positioned for the action of the parter and clamp.

An important feature of the present invention, therefore, consists of a filling thread positioning member having a yielding or brush-like filling engaging surface which is

positioned for engagement with the filling upon call for filling replenishment when the shuttle is in the replenishing box.

In carrying this feature of the invention into practical effect, the positioning member extends transversely of the lay between the cloth selvage and shuttle-box, and is provided with a brush-like surface or bristles which project upwardly therefrom, but which are normally below the race or path of the shuttle, the effect being that the brush-like surface or bristles carried by the positioning member effectively hold the filling thread and move it to a position for engagement by the parter and clamp, and furthermore, serve to provide a bight or bend of filling thread as the lay beats up, which furnishes sufficient length of filling thread between the cloth selvage and parter and clamp, so that when the latter is moved to its front position, liability of breaking the filling thread leading from the cloth selvage is obviated. These bristles or brush-like surface on the positioning member may be variously contrived, but in practice it is found that by inclining the bristles frontwardly from the positioning member, they serve to more effectively hold and position the filling thread, because any tension thereon serves to embed the thread further into the brush-like surface or bristles.

Other features of the invention and novel combination of parts will be described in addition to the above, and in connection with the accompanying drawing, which illustrates a good practical form of the invention.

In the drawing:

Figure 1 is a section through a loom from front to rear, showing the present invention associated therewith, and illustrating only sufficient of the parts of the loom to make clear the construction and mode of operation;

Fig. 2 is a plan view showing the two positions of parts to be described, in rear and front positions by dotted and full lines respectively; and

Fig. 3 is a perspective detail on an enlarged scale, showing the filling thread positioning member and its brush-like surface.

The loom frame 1 has mounted thereon the usual brackets 2, one at each side of the loom for supporting the transverse or rock shaft

3, which on call for replenishment of filling by any usual type of feeler mechanism now well understood in the art, is given a rocking movement clockwise in the direction of the arrow (Fig. 1). Extending backwardly from the shaft 3 is the arm 4 which bears upon a pin 5 extending from the usual shuttle feeler 6 which may be pivoted at 7 to a bracket 8 secured to the loom frame. It is usual to hold the shaft 3 under spring tension, and to effect its movement clockwise against the tension of the spring. In the present instance, the arm 4 has pivotally connected thereto at 9 a lever 10, the rear end 11 of which receives between it and the under surface of the arm 4, the pin 5, heretofore mentioned. The front end of the lever 10 is connected to a spring 12 which normally exerts a downward pull to maintain the arm 4 and lever 10 in engagement with the pin 5, and hold the rock shaft 3 under spring tension. The construction thus far described is of usual character and associated with the shuttle feeler 6 is a filling thread cutter and clamp. In the present instance, the cutting member as indicated at 13 is pivotally mounted at 14 upon the shuttle feeler 6. The clamping member 15 is located at the side of the parter or cutting member 13 and is adapted to pinch or hold the end of the filling leading from the cloth selvage when it has been parted or cut by the parter 13. The rear end portion of the shuttle feeler is provided with the usual entrance inclines 16 (Fig. 1) into which the filling leading from the cloth selvage to the shuttle should pass when the feeler and cutter and clamp move rearwardly to operative position. The shuttle feeler and its associated parter and clamp may be of any usual character, several forms of these parts being now well known and understood by those skilled in the art.

The lay 17 is mounted upon the usual swing arms or swords 18, and moves from a rearward to a forward position on each beat-up as usual.

Supported by suitable means, usually from the loom frame or breast beam is the loom temple 19 having a temple thread cutter 20 which severs or cuts the end of the filling close to the cloth selvage. The lay 17 is provided with a recess 21 extending transversely thereof across the race or path of the shuttle 22. The filling thread positioning member consists of a support on which is mounted a yielding filling engaging surface, such support normally lying in the groove or recess 21 to position the filling engaging surface below the plane of the race or path of the shuttle. In the present instance, the positioning member comprises an arm 23 which is guided for movement in an upwardly direction relative to the race or path of the shuttle by means such as a guide or

bearing 24 secured, in the present instance, by screws 25 to the front surface of the lay. The arm 23 at its upper end has connected thereto the transversely extending portion 26, preferably of suitable dimensions to be received in the groove or recess 21, and secured to the portion 26 of the positioning member are the bristles or yielding projections 27. The yielding filling engaging surface or bristles 27 extend upwardly from the portion 26 of the positioning member, and are preferably inclined forwardly, to thereby more effectively and unerringly hold the filling thread when it is engaged thereby. Owing to the yielding nature of the filling engaging surface of the positioning member, no injury is done the shuttle should it strike or move in contact with such surface as it is picked. In such case the yielding surface or bristles 27 will yield.

During the regular weaving operation, when a supply of filling is present in the shuttle, the positioning member is in its lowered position, and the yielding surface or bristles are carried downwardly below the race or shuttle path. When, however, filling is to be replenished, it is desirable to raise the positioning member for engagement with the filling to (1) position the filling for the action of the parter and clamp, and (2) furnish slack between the cloth selvage and clamp to permit the latter to move the end of the filling forwardly without danger of breaking the filling between the cloth selvage and clamp, and position it for the action of the temple thread cutter.

The shuttle 28 is picked from the non-replenishing side of the loom when the lay is near its back position as indicated by dotted lines in Figs. 1 and 2, and the filling thread then leads from the cloth selvage on the side of the loom opposite the replenishing box in an inclined direction as indicated by the dotted line *a* (Fig. 2), the shuttle usually reaching the box as indicated by dotted lines while the shuttle is near its rear position or starting its forward movement. On call for replenishment of filling, it is desirable that the positioning member be raised before the lay reaches its front position, or while it is near its rear position, in order to cause the filling thread *a* to be engaged by the yielding surface or bristles near the front portion of the lay, to thereby form a bight or bend in the filling thread *a* between the cloth selvage and shuttle, as the lay beats up and furnish sufficient length of thread between the selvage and thread clamp to enable the latter to move to front position without breaking the thread.

To thus raise the positioning member, the arm 23 thereof is prolonged downwardly to furnish the rounded end portion 29, and

the arm 4 leading from the transverse or change shaft 3 is prolonged rearwardly as at 30 (Figs. 1 and 3) to provide a cam or inclined surface 31 over which the end 29 of the positioning member may travel as the lay moves forwardly.

During weaving with a working supply of filling present in the shuttle, the rearwardly extending portion 30 of the arm 4 is in its lower or dotted line position as indicated in Fig. 1, below the path of movement of the end 29 of the thread positioning member. When, however, a call for replenishment of filling occurs, the shaft 3 is turned clockwise, as usual, thereby lifting the end 30 of the arm 4 into the path of movement of the end 29 of the positioning member, and as the lay starts forwardly, the positioning member will be raised to project its yielding surface or bristles 27 above the race or path of the shuttle just after the shuttle has passed or been boxed. The effect is that the filling thread *a* will be engaged by the yielding surface or bristles 27 at a point near the front of the lay as at *b* (Figs. 3 and 2), and as the shuttle feeler moves rearwardly to feel for the shuttle, it will form a bight or bend in the filling thread *a* between the cloth selvage and the shuttle, as indicated in Fig. 2. The yielding surface or bristles 27 thus raise or position the filling thread for the action of the parter and clamp, and provide sufficient length of thread in the filling between the cloth selvage and clamp to avoid breaking such thread between the cloth selvage and clamp, as the latter returns to its front position, thereby positioning the intact filling for the action of the temple thread cutter and in case the bristles should for any reason be struck by the shuttle they will yield and not injure the shuttle. After replenishment of filling, the rock shaft 3 returns to its normal position to carry the arm 4 downwardly to dotted line position (Figs. 1), and the filling thread positioning member returns to its lower position.

By inclining the bristles 27 forwardly as indicated in Figs. 1 and 3, the filling thread *a* will be depressed into the bristles more readily by any tension placed thereon due to the rearward movement of the shuttle feeler and thread cutter and clamp.

What is claimed is:—

1. In a filling replenishing loom, the combination of the lay and shuttle-boxes, a thread parter and clamp to part and clamp the old or spent filling between the cloth selvage and shuttle, means for moving the parter and clamp rearwardly to operative position on call for replenishment of filling and then forwardly to position the end of the filling leading from the cloth selvage for the action of the temple thread cutter, a filling thread positioning device mounted

on the lay and having a thread engaging surface that is formed of forwardly inclined bristles which engage the filling thread and form a bend therein between the cloth selvage and thread parter and clamp, and provide sufficient thread to permit the parter and clamp to carry the end of the filling forwardly without breaking it.

2. In a filling replenishing loom, the combination of the lay and shuttle-boxes, a thread parter and clamp to part and clamp the old or spent filling between the cloth selvage and shuttle, means for moving the parter and clamp rearwardly to operative position on call for replenishment of filling and then forwardly to position the end of the filling leading from the cloth selvage for the action of the temple thread cutter, a filling thread positioning device mounted on the lay between the cloth selvage and shuttle-box and having a thread engaging surface that is formed of forwardly inclined bristles which engage the filling thread and form a bend therein between the cloth selvage and thread parter and clamp as the lay beats up, and provide sufficient thread to permit the parter and clamp to carry the end of the filling forwardly without breaking it, and means for operatively positioning the positioning device on call for replenishment of filling.

3. In a filling replenishing loom, the combination of a lay and shuttle-boxes, means for parting the old or spent filling between the cloth selvage and shuttle when the filling is to be replenished, a filling thread positioning member that is carried by the lay and has a brush-like surface for engaging and positioning the filling, and means for moving the said member to place the brush-like surface in position to engage the filling only when the filling is to be replenished.

4. In a filling replenishing loom, the combination of the lay and shuttle-boxes, a filling thread parter, a thread positioner that is mounted on the lay and has a series of bristles or brushes extending upwardly therefrom but normally below the surface of the race or shuttle path, and means operative on call for replenishment of filling to raise the bristles or brushes for engagement with the filling.

5. In a filling replenishing loom, the combination of the lay and shuttle-boxes, a filling thread parter, a thread positioner that extends in a direction transversely of the lay and has a series of bristles or brushes extending upwardly therefrom adapted to yield by contact with the shuttle and avoid injury thereto, and means for causing the bristles or brushes to engage the old or spent filling and place it in position for the thread parter when filling is to be replenished.

6. In a filling replenishing loom, the combination of the lay and shuttle-boxes, means

for parting the old or spent filling between the cloth selvage and shuttle when in the adjacent shuttle box, a filling thread positioning device mounted on the lay transversely thereof and having a yielding surface to engage the filling between the cloth selvage and shuttle when replenishment of filling is to be effected.

7. In a filling replenishing loom, the combination of the lay and shuttle-box, means for parting the filling between the cloth and shuttle-box, a filling thread positioning device that is mounted on the lay transversely of the race or shuttle-box and has a filling 5 engaging surface formed by flexible projections extending therefrom, and means for causing the flexible projections to engage and position the filling for the action of the

parting means on call for replenishment of filling.

8. In a filling replenishing loom, the combination of a thread parter and clamp, the lay and shuttle-boxes, a brush-like surface extending transversely of the lay below the race or shuttle path, and means for causing the brush-like surface to engage the filling thread near the front of the lay and hold it as the lay beats up to thereby form a bend in the filling thread between the cloth selvage and clamp and provide sufficient thread 25 to enable the clamp to carry the end of the filling frontwardly without breaking it.

In testimony whereof, I have signed my name to this specification.

FRED LACEY.
